DISTRIBUTOR STRUCTURE

Harold P. Faris, Philadelphia, Pa., and John E. White, Trenton, N. J., assignors to National Automotive Fibres, Inc., Detroit, Mich., a corporation of Delaware

Original application October 28, 1940, Serial No. 363,196. Divided and this application April 24, 1943, Serial No. 484,431

12 Claims. (Cl. 91—8)

This invention relates generally to carpet making machines for manufacturing carpet of the type disclosed in United States Patent No. 2,187,140, dated January 16, 1940, and constitutes a division of our application filed October 28, 1940, bearing Serial No. 363,196.

One of the essential objects of the invention is to provide an improved distributor for feeding cut fibers, such as cut hair and the like, onto a cement coated surface of suitable carpet material, such as a burlap covered base of rubber, while the carpet material is being vibrated so that the vibration will cause the fibers discharged from the distributor to be imbedded endwise in the cement to simulate the pile of a conventional woven carpet.

Another object is to provide a distributor wherein fibers admitted to the upper portion thereof are adapted to be distributed substantially uniformly to the lower portion thereof.

Another object is to provide a distributor having an elongated casing adapted to extend transversely over advancing cement coated carpet material and having means within the upper portion of the casing for directing portions of the fibers admitted thereto toward opposite ends of the casing.

Another object is to provide a distributor wherein the directing means just mentioned is adapted to be adjusted to various positions for varying the distribution of the fibers, and is capable of being locked in any desired adjusted position.

Another object is to provide a distributor wherein the directing means includes a plurality of hingedly mounted deflector plates which may be simultaneously adjusted by a single manually operable member.

Another object is to provide a distributor that is simple in construction, economical to manufacture, easy to install and efficient in operation.

Other objects, advantages and novel details of construction of this invention will be made more apparent as this description proceeds, especially when considered in connection with the accompanying drawings, wherein:

Figure 1 is a side elevation of a machine for making carpet and having a distributor embodying our invention;

Figure 2 is an elevational view of the distributor;

Figure 3 is an end view of the distributor illustrated in Figure 2;

Figure 4 is a vertical sectional view through the upper portion of the distributor illustrated in Figures 1 and 2;

Figure 5 is a view partly in vertical section of the structure illustrated in Figure 4, and showing by dotted and full lines different positions of adjustment for the pivoted deflector plates.

Referring now to the drawings, A is a distributor embodying our invention and constituting a part of a machine illustrated generally in Figure 1 for manufacturing carpet of the cemented pile type.

10 As shown in Figure 1, the carpet material 10, such as burlap covered rubber, is advanced through the machine with the burlap side thereof uppermost so that the upper surface of the burlap may be coated or covered with an adhesive substance or cement as the material passes through an adhesive applying mechanism 11.

15 Cooperating belts 12 and 13 respectively are employed for withdrawing the carpet material 10 from a roll 14, and other conveyor means including a belt 15 is employed for advancing the carpet material through the adhesive applying mechanism 11 and over suitable rotary beaters 16 which vibrate the material after the adhesive substance is applied to the upper surface thereof.

20 Cut fibers such as cut hair or the like are discharged from the distributor A, and from a rotary sieve (not shown) located between the adhesive applying mechanism 11 and the distributor A onto the adhesive coated carpet material as it is vibrated so that such fibers will be imbedded in the adhesive coating to form the cemented pile carpet. If desired the fibers supplied to the distributor A constituting the second point of application, may be excess fibers from the sieve mentioned constituting the first point of application. Moreover, such excess fibers may be mixed with a certain percentage of freshly cut fibers for the second application.

25 Preferably the distributor A has a casing 20 that is relatively narrow and elongated in configuration so as to extend transversely over the advancing carpet material 10 on the belt 15, hingedly mounted deflector plates 21 for directing a portion of the cut fibers toward opposite ends of the casing 20, and rotary saw-toothed blades (not shown) for breaking up balls, pills or other formations of the cut fibers.

30 The casing 20 is provided at its upper end with an inlet 30 through which the cut fibers are adapted to pass from a collector or other suitable source of supply (not shown), and has an open lower end 31 through which the cut fibers are adapted to be discharged onto the adhesively coated carpet material 10. 32 are windows in one side of the casing 20 through which the

operator can inspect the mechanism within the casing, and 33 are removable panels which may be in the same or another side of the casing to afford access to the interior thereof.

Preferably the upper portion 34 of the casing is inverted V-shape in configuration, and the inlet 30 is at the apex of the V, while the lower portion 35 of said casing is substantially rectangular shape in configuration.

The deflector plates 21 are in the upper portion 34 of the casing and are adapted to direct some of the fibers from the inlet 30 toward opposite ends of the casing 20. Preferably these plates 21 are hinged at their upper ends upon horizontal pivot shafts 36 carried by the casing and are pivotally connected adjacent their lower ends to links 37 that extend laterally from and are pivoted to levers 38 and 39 respectively keyed or otherwise non-rotatably mounted on shafts 40 and 41 journaled in brackets 42 and 43 carried by the casing. Meshing pinions 44 and 45 are fixed to the shafts 40 and 41, and a hand lever 46 is fixed to the shaft 40. Thus, when the hand lever 46 is swung in the arc of a circle, the pinions 44 and 45 will cause the shafts 40 and 41 to rotate in unison and thereby swing the levers 38 and 39, links 37 and deflector plates 21 simultaneously as indicated by full and dotted lines in Figure 5. A plate 47 is rigidly secured to the bracket 42 beside the hand lever 46 and has an arcuate slot 48 therein substantially concentric to the axis of the shaft 40, while a bolt 49 extends through the slot 48 in the plate 47 and through the hand lever 46 and is engaged upon the outer side of the latter by a winged nut 50. Hence the winged nut 50 may be adjusted on the bolt 49 to hold the hand lever 46 in adjusted position.

In use, the fibers may be supplied to the inlet 30 of the casing 20 by any suitable means (not shown). Portions of these fibers will be directed by the deflector plates 21 toward opposite ends of the casing 20 disposed over opposite side edges of the advancing carpet material 10, while other portions of the fibers will fall between the pivots 36 at the center of the casing. The deflector plates 21 may be swung to the desired inclined position by the hand lever 46 and then may be held in such adjusted position by tightening the winged nut 50. Upon reaching the lower portion 35 of the casing the fibers aforesaid will engage the rotating saw-toothed blades (not shown) which will distribute the same downwardly through the lower open end of the casing onto the advancing adhesive coated carpet material 10. If some of the fibers have gathered into balls, pills or other objectionable formations, the saw-toothed blades (not shown) will effectively break up such balls, pills, etc., so that the separated fibers in substantially free or loose condition will be distributed downwardly through the open end of the casing onto the cement coated carpet material. Thus, all of the fibers discharged from the lower end 31 of the casing will be free and loose and will be distributed with substantial uniformity onto the carpet material.

What we claim as our invention is:

1. A distributor of the class described having a casing provided at the top thereof with an inlet and provided at the bottom thereof with an outlet, spaced deflector plates pivoted at their upper ends adjacent the inlet for directing fibers from the inlet toward certain areas of the outlet, a pair of shafts carried by the casing, meshing gears on said shafts, levers fixed to said shafts, links connecting the levers to said plates, and means

for turning one of said shafts to cause simultaneous movement of the levers, links and plates.

2. A distributor of the class described having a casing provided at the top thereof with an inlet and provided at the bottom thereof with an outlet, spaced deflector plates pivoted at their upper ends adjacent the inlet for directing fibers from the inlet toward certain areas of the outlet, a pair of shafts carried by the casing, meshing gears on said shafts, levers fixed to said shafts, links connecting the levers to said plates, an operating lever fixed to one of said shafts, and means engageable with said operating lever to hold the levers, links and plates against movement.

3. A distributor having a casing provided at the top thereof with an inlet and provided at the bottom thereof with an outlet, and means within the casing for distributing toward opposite ends of the outlet fibers admitted to the inlet, including a plurality of hingedly mounted deflector plates, a pair of meshing gears, an operating member for said gears connected to one of them, levers rigid with said gears, and links terminally connected to said plates and levers.

4. A distributor having a casing provided at the top and bottom thereof with an inlet and an outlet respectively for fibers, spaced pivots carried by said casing just below said inlet, deflector plates suspended from said pivots and extending downwardly within said casing for directing fibers from the inlet toward certain areas of said outlet, the upper ends of said deflector plates terminating at said spaced pivots so that a space is provided therebetween in registration with the inlet for the passage of some of the fibers from the inlet, spaced shafts below and substantially parallel to the pivots for the deflector plates, and means operable by said shafts and connected to said deflector plates adjacent their lower ends for actuating the same about the axes of their pivots.

5. A distributor for fibers having a casing provided at the top thereof with an inlet and provided at the bottom thereof with an outlet, laterally spaced pivots carried by the casing across and just below the inlet, deflector plates suspended from said pivots and extending downwardly within said casing for directing fibers from the inlet toward certain areas of the outlet, the upper ends of said deflector plates terminating at said pivots, and means for adjusting the deflector plates about the axes of their pivots, the lateral spacing and location of said pivots and the termination of said deflector plates at said pivots being such that a space for fibers from the inlet is provided beneath and in registration with said inlet so that portions of the fibers from the inlet may fall in said space between the pivots and deflector plates to the outlet without being directed by said plates, while other portions of said fibers from the inlet will be directed by the deflector plates as aforesaid.

6. A distributor for fibers having a casing provided at the top thereof with an inlet and provided at the bottom thereof with an outlet, laterally spaced pivots carried by the casing across and just below the inlet, deflector plates suspended from said pivots and extending downwardly within said casing for directing fibers from the inlet toward certain areas of the outlet, the upper ends of said deflector plates terminating at said pivots, the lateral spacing and location of said pivots and the termination of said deflector plates at said pivots being such that a space for fibers from the inlet is provided beneath and

in registration with said inlet so that portions of the fibers from the inlet may fall in said space between the pivots and deflector plates to the outlet without being directed by said plates, while other portions of said fibers from the inlet will be directed by the deflector plates as aforesaid, an operating member, and means actuatable by said member for adjusting said deflector plates about the axes of their pivots.

7. A distributor having a casing provided at the top and bottom thereof with an inlet and an outlet respectively for fibers, the top portion of the casing containing the inlet being inverted substantially V-shape in cross section with the inlet at approximately the apex of the V, laterally spaced pivots carried by said casing below said inlet, deflector plates suspended from said pivots and extending downwardly within said casing for directing fibers from the inlet toward certain areas of the outlet, spaced shafts below and substantially parallel to the pivots for the deflector plates, meshing gears on said shafts, levers fixed to said shafts, links connecting the levers to said deflector plates, and means for turning one of said shafts to cause simultaneous movement of the levers, links and deflector plates.

8. A distributor having a casing provided at the top and bottom thereof with an inlet and an outlet respectively for fibers, laterally spaced pivots carried by the casing across and below the inlet, deflector plates suspended from said pivots and extending downwardly within said casing for directing fibers from the inlet toward certain areas of the outlet, spaced shafts between said deflector plates, meshing gears on said shafts, levers fixed to said shafts, links connecting the levers to said deflector plates, and means for turning one of said shafts to cause simultaneous movement of the levers, links and deflector plates.

9. A distributor having a casing provided at the top and bottom thereof with an inlet and an outlet respectively for fibers, spaced pivots carried by the casing across and below the inlet, deflector plates suspended from said pivots and extending downwardly within said casing for directing fibers from the inlet toward certain areas of the outlet, the upper ends of said deflector plates terminating at said spaced pivots to provide therebetween a space in registration with said inlet, spaced shafts between said deflector

plates, meshing gears on said shafts, levers fixed to said shafts, links connecting the levers to said deflector plates, and means for turning one of said shafts to cause simultaneous movement of the levers, links and deflector plates.

10. A distributor having a casing provided at the top and bottom thereof with an inlet and an outlet for fibers, two pivots spaced laterally apart below the inlet, deflector plates suspended from said pivots and extending downwardly within said casing for directing fibers from the inlet toward certain areas of the outlet, the upper ends of said deflector plates terminating at said pivots to provide therebetween a space in registration with the inlet for the passage of fibers, a pair of shafts spaced laterally apart below the pivots, levers fixed to said shafts, links connecting the levers to said deflector plates, and a driving connection between said shafts operable to move the levers, links and deflector plates simultaneously.

11. A distributor having a casing provided at the top and bottom thereof with an inlet and an outlet for fibers, two pivots spaced laterally apart below the inlet, deflector plates suspended from said pivots and extending downwardly within said casing for directing fibers from the inlet toward certain areas of the outlet, the upper ends of said deflector plates terminating at said pivots to provide therebetween a space in registration with the inlet for the passage of fibers, a pair of shafts spaced laterally apart below the pivots, levers fixed to said shafts, links connecting the levers to the deflector plates, and means for actuating said shafts to move the levers, links and deflector plates.

12. A distributor having a casing provided at the top and bottom thereof with an inlet and an outlet for fibers, two pivots spaced laterally apart below the inlet, deflector plates suspended from said pivots and extending downwardly within said casing for directing fibers from the inlet toward certain areas of the outlet, a pair of shafts spaced laterally apart below the pivots, levers fixed to said shafts, links connecting the levers to the deflector plates, and means for actuating said shafts to move the levers, links and deflector plates.

HAROLD P. FARIS.
JOHN E. WHITE.
